UNITED STATES PATENT OFFICE

GEORGE F. WHITEHEAD, OF SIOUX CITY, IOWA

RECEPTACLE FOR ICE MANUFACTURE

Application filed January 13, 1932. Serial No. 586,432.

The present invention relates to a receptacle of fibrous material, such as paper, in which water is adapted to be frozen under natural temperature conditions and the resulting ice stored while contained in the receptacle, and more particularly to a specific construction of receptacle designed to permit its expansion during the freezing of contained water and thus prevent rupture thereof.

My invention has in view the present day serious difficulty of farmers and others in rural districts to secure ice during the warm summer months and has for its purpose the provision of a simple and novel container of the type specified which will be capable of utilization by anyone with the aid only of an ordinary storage ice house. My invention maintains all of the hygienic qualities of modern manufactured ice while being produced individually at the home of the user without any equipment except the containers which not only afford the medium for holding the liquid for freezing but materially aid in insulating the ice cakes during storage.

In the accompanying drawing:

Figure 1 is a perspective view showing the method of storing ice in accordance with my invention;

Figure 2, a detail sectional view of two of the ice filled containers showing the mode of mounting one upon the other;

Figure 3, a cross-sectional view taken through one of the containers showing the same with water therein; and

Figure 4, a detail sectional view of one corner of the container showing means providing for the expansion of the water during freezing.

A very serious problem is found to exist in rural districts, especially on farms having no pond from which ice blocks may be cut in freezing weather, in obtaining and storing ice for use in the warmer months. My invention is therefore directed to the provision of means whereby this difficulty is overcome and has for its general concept to make this means of such simplicity that the same may be practiced by an individual whether skilled or not.

The containers are made from a cheap fibrous stock, the only prerequisite being the capability to hold water and are preferably formed with an open top. In storing the containers with the ice therein, they are stacked one upon another, so that the bottom of each acts as a top for the one immediately below and the sides insulate one cake from another, thus serving not only to prevent the ice from melting, but facilitating the separation of individual cakes from the stack.

With reference to the accompanying drawing I have shown the several containers 10 of rectangular form provided with sides 11 and a closed bottom portion 12. These containers as stated hereinbefore must necessarily be water tight and may be constructed of comparatively inexpensive materials such as fibrous paper stock. To aid in the non-porosity of the materials used in the containers the same may be coated with wax or some similar material and when wax is used, this acts as a medium to prevent the several containers when stacked from freezing one to the other. It is of course obvious that the wax will also aid in the separation of any one container from the storage stack. I preferably form the containers 10 with an open top 13.

In producing the ice cakes within the container, the most economical way for people in rural districts is to fill the same with water to a certain level and then place the container in a freezing temperature. It is known that water expands a certain amount when formed into ice and I have thus, as shown in Figure 3, determined a certain level for the water to compensate for this expansion and to provide ice within the entire inside dimension of the container upon freezing. The containers as manufactured may be provided with suitable marking or scoring as at 14 to indicate the proper level of the water.

In Figure 4 I have shown as a modification a section of a container provided with means automatically compensating for the expansion of water during freezing. These means consists merely in providing the sides of the container 15 with recesses 16 which will serve to confine the water within the container, but

permit lateral expansion upon the freezing of the water. These recesses are calculated to a depth to compensate for the amount of such expansion and the resulting cake of ice ⁵ will be a true cube.

As previously stated each of the several containers 10 are provided with open tops 13 and in the storing of the ice containers they are placed directly one upon the other. ¹⁰ Hence, as will be seen from an inspection of Fig. 2, the bottom 12 of each container forms an insulating seal for the top of the ice cake in the container immediately below. If desired, certain of the containers 10 may be ¹⁵ provided with separate or integrally connected top pieces 17, these being especially useful in the uppermost layer of containers when stacked for storage and serve to prevent contact of the storage insulating material such as straw, saw-dust and the like from coming into contact with the ice. ²⁰

I claim:

A receptacle for freezing water therein and facilitating the storing of resulting ice, said ²⁵ receptacle having an open top and the sides of the receptacle each being dished from adjacent corners and bottom edge of the receptacle with each corner edge of the receptacle constituting a common edge of the dish formations of adjacent sides to permit lateral expansion of the receptacle during the process of freezing its contents. ³⁰

In testimony whereof I hereunto affix my signature.

35 GEORGE F. WHITEHEAD.
